UNITED STATES PATENT OFFICE.

SIDNEY M. ISRAEL, OF RICHMOND HILL, NEW YORK.

DESIGN FOR A CEILING-PLATE FOR ELECTRIC-LIGHT FIXTURES.

56,877.

Specification for Design.

Patented Jan. 4, 1921.

Application filed June 25, 1920. Serial No. 391,821. Term of patent 7 years.

To all whom it may concern:

Be it known that I, SIDNEY M. ISRAEL, a citizen of the United States, residing at Richmond Hill, county of Queens, and State of New York, have invented a new, original, and ornamental Design for Ceiling-Plates for Electric-Light Fixtures, of which the following is a specification, reference being had to the accompanying drawing, forming part thereof.

The figure is a perspective view of an electric light fixture, showing my new design.

I claim:

The ornamental design for a ceiling plate for electric light fixtures as shown.

SIDNEY M. ISRAEL.
